J. TYLER.

Water Wheel.

No. 12,927.

Patented May 22, 1855.

UNITED STATES PATENT OFFICE.

JOHN TYLER, OF WEST LEBANON, NEW HAMPSHIRE.

CURB FOR WATER-WHEELS.

Specification forming part of Letters Patent No. 12,927, dated May 22, 1855.

To all whom it may concern:

Be it known that I, JOHN TYLER, of West Lebanon, in the county of Grafton and State of New Hampshire, have invented a new and useful Improvement in the Curbs of Water-Wheels; and I do hereby declare that the following is a full and exact description thereof, reference being had to the accompanying drawings, making a part of this specification.

The water-wheel curb to which I have made an improvement is of such a shape as to form a scroll water-way around the wheel; and my improvement consists in terminating the said scroll water-way by a movable lip *b* of such a shape that its inner curved surface brings the scroll to a point at the periphery of the wheel when the lip is closed and whose straight surface forms one side of the mouth *A* of the said scroll water-way. The lip *b* works on the hinge *c*. The closed position of said lip is represented in Fig. 2 and its open position in Fig. 3. It will be perceived that the pressure and friction of the water as it passes into the mouth of the scroll water-way will keep the lip *b* in its closed position, and should any obstruction be drawn into the wheel and be

brought in contact with the said lip *b* it will be thrown open, and thus prevent injury to the curb or to the buckets of the wheel. This improvement also enables the outer extremity of the lip *b* to be brought much closer to the extremities of the buckets of the water-wheel than it would be safe to do, if it were a solid portion of the curb, which causes the water to act with greater efficiency upon the wheel.

What I claim as my invention, and desire to secure by Letters Patent, is—

Combining the within-described hinged lip *b* with the curb of a water-wheel in such a manner that its inner curved surface forms the termination of the scroll water-way surrounding the wheel, while its straight surface forms one side of the mouth of the said scroll water-way, for the purposes herein set forth.

The above specification of my improvement in the curbs of water-wheels signed and witnessed this 17th day of February, 1855.

JOHN TYLER.
